O. HACKENBERG

BOW SHUTTLE

Filed July 1, 1925

WITNESS

W. M. Bell

INVENTOR,

Otto Hackenberg,
BY
John Edward
ATTORNEY

UNITED STATES PATENT OFFICE.

OTTO HACKENBERG, OF PATERSON, NEW JERSEY.

BOW SHUTTLE.

Application filed July 1, 1925. Serial No. 40,785.

To all whom it may concern:

Be it known that I, OTTO HACKENBERG, a citizen of the United States, residing at Paterson, in the county of Passaic and State 5 of New Jersey, have invented certain new and useful Improvements in Bow Shuttles, of which the following is a specification.

Bow shuttles for ribbon looms are usually constructed of wood, sometimes all in one piece but usually with the runner or body portion of one piece and the bow of another. Such shuttles are weak and frequently fracture across the bow which it is necessary to carve out from a block of the wood; they 10 require very skillful labor and a considerable amount of time to form them, particularly with respect to the shaping of the bow and fitting it to the runner; they are unduly heavy and also thick in the bow, so that they 15 begin in a short time to sag and cause wear of the shuttle grooves and the blocks in which the shuttles travel and they are likely to rub on the warp threads to a harmful extent; and their provision for guiding the 20 filling tension springs is such that the delicacy of action of such springs is impaired. The object of this invention is to provide a 25 bow shuttle which shall represent an improvement on ordinary bow shuttles in all 30 these respects.

To this end I form the runner or body portion of the shuttle of wood, as usual, but the bow I form of a tough, grainless material, such as fibre, which is preferred be- 35 cause it is light in weight. My invention in part consists in a shuttle of the bow type having a runner and a bow secured thereto which is formed of a strip of grainless mate- 40 rial, as fibre, bent to the bow-shape. The in- vention further consists in certain combina- 45 tions of parts concerned with the joining of the bow to the runner and the guiding of the tension springs for the filling.

In the drawing,

Fig. 1 is an underneath plan of my im- 45 proved shuttle, partly in section;

Fig. 2 is a front elevation thereof;

Fig. 3 is a top plan view; and

Fig. 4 a section on line 4—4, Fig. 2.

The runner 1 of the improved shuttle may 50 have substantially the same form as the runner of the ordinary bow shuttle, its under side being formed with a longitudinal groove 2 having the usual toothed driving rack 2^a 55 and its top side having the longitudinal

guide groove 3. The runner will usually be formed of hard wood.

To form the bow 4 I take a straight strip of fibre and bend it to the form of a bow, preferably with its end portions approxi- 60 mately perpendicular to the same plane. The ends 5 of these end portions are cut off smooth so as to coincide with such plane; dowel holes 6 are formed in said end portions; holes 7 are formed through the end portions so as to converge with respect to each other; and certain other operations are performed on the bow (for the mounting of the filling package and guiding of the filling, as will appear), and it will be understood 65 that it is not material so far as the invention itself is concerned whether these are done before the strip to form the bow is bent into shape or at any other stage in the opera- 70 tion of forming the finished shuttle. 75

Dowel holes 8 are formed in the front face of the runner to match the holes 6 in the ends of the bow, and these and the said holes 6 receive dowels 9, preferably of metal, whereby the bow is joined to the runner. Other holes 10 are formed in the front face of the runner, each preferably between the bow and the adjoining end of the runner. These holes 10 and the holes 7 are made to receive tubes 11 of metal which are bent and 80 serve both as dowels and, as will appear, as guides for the tension springs of the shuttle. The dowels 9 and 11 of course fit the holes very snugly; and one advantage of the dowels 11 is that since they are bent they 85 obtain a good hold on the bow, the joint between the bow and shuttle thereby being very greatly reinforced by them.

The holes 10 are counterbores of holes 12 which extend clear through the runner from front to rear. Through each such hole 12 and the corresponding tubular dowel 11 ex- 90 tends a spiral spring 13 one end of which is secured in the usual way to the back of the shuttle by a brad 14 and the other end of which carries a ring guide 15 of a di- 95 ameter too great to enter the hole 7. The bends in the tubular dowels 11 are prefer- ably gradual curves. Ordinarily these springs extend through holes formed longi- 100 tudinally in the legs or end portions of the bow and emerging at the inner surfaces of such legs in such manner that each spring assumes a sharp bend where it protrudes, wherefore the spring does not act for its full 110

extent and the delicacy of the tension is impaired; an advantage in bending each dowel 11 in a curve is that the full length of the spring remains available.

5 The filling package 16 is arranged as usual on a spindle 17 having one end 17^a (Fig. 2) bent off, this end being fitted to slot 18 in one leg of the bow and the other entered into a hole 19 in the other leg. In the arch 13 of the bow is the delivery eye 20 through which the thread A from the filling package extends after successively passing through the eyes or guides 15 and a ring guide or eye 21 attached by a clip 22 to the bow. 23 is the usual brake device for the package.

29 Since the bow itself is of grainless material it is very strong and is not susceptible of injury. It may be thinned down to whatever extent required (see the front elevation, Fig. 2) so as to avoid as much as possible its rubbing on the warp.

By forming the bow from a strip of grainless material bent to bow form I avoid the labor incident to a molding operation and 25 also the likelihood of such (molded) bow warping out of shape in course of time, which would certainly occur in the case where the legs of the bow are not greatly thickened up but for the sake of lightness 30 are formed only thick enough to afford good dowel joints between the bow and runner, as herein illustrated.

35 Ordinary bow shuttles are necessarily heavy in the bow, which causes such a wearing away of the shuttle grooves 2 and 3 and the corresponding parts of the shuttle blocks in which they travel that the shuttles sag in time.

40 In bow shuttles in which the runner and bow are separate parts joined together and the ends of the bow abut an exterior surface of the runner the filling frequently catches in the crevices which in the use of the shuttle form in time between the runner and the 45 ends of the legs of the bow. The devices 11, being each arranged between the end of the runner and leg of the bow, prevent this in my improved shuttle.

Having thus fully described my invention 50 what I claim and desire to secure by Letters Patent is:

1. In a shuttle, the combination of a runner, a bow having its ends adjoining the runner, and a dowel fitted at one end in the runner and having its other end bent off and fitted in an end portion of the bow.

2. In a shuttle, the combination of a runner, a bow having its ends adjoining the runner, and a dowel fitted at one end in the runner lateral of one end portion of the bow and having its other end portion bent off and fitted into such end portion of the bow. 60

3. In a shuttle, the combination of a runner, a bow having its ends adjoining the runner, and a dowel fitted at one end in the runner between one end portion of the bow and the adjoining end of the runner and its other end portion bent off and fitted into such end portion of the bow. 65

4. In combination, with a shuttle structure including a runner, a bow having its ends adjoining the runner and a hole therethrough emerging at an exposed surface of the bow and a tubular dowel fitted into said hole and into the runner and thereby joining the runner and bow, a tension device arranged in the dowel and including a spring secured to the shuttle structure for tensioning. 70

5. In combination, with a shuttle structure including a runner, a bow having its ends adjoining the runner and a hole extending through the bow from one exposed surface to a substantially opposite exposed surface thereof and a tubular dowel having one end fitted into the runner lateral of the bow and its other end bent off and fitted in said hole, a tension device arranged in the dowel and including a spring secured to the shuttle structure for tensioning. 75

6. In combination, with a shuttle structure having a runner portion and a bow portion and a hole in the bow portion extending therethrough from one exposed surface to a substantially opposite exposed surface thereof and a tubular device having one end fitted into the runner portion lateral of the bow portion and its other end bent off and fitted in said hole, a tension device arranged in said tubular device and including a spring secured to the shuttle structure for tensioning. 90

7. In a shuttle, the combination of a runner, a bow having its ends adjoining the runner and abutting an exterior surface thereof, and a guard bridging the angle between one of the legs of the bow and the adjacent end portion of the runner and fitted into each of them. 105

In testimony whereof I affix my signature.

OTTO HACKENBERG.
